United States Patent Office

Des. 202,629
Patented Oct. 26, 1965

202,629

GAME PANEL

Frederick A. Hurley, 10911 NE. 10th Ave., Miami, Fla.

Filed Sept. 8, 1964, Ser. No. 81,613

Term of patent 14 years

(Cl. D34—5)

FIGURE 1 is a top plan view of a game board showing my new design, with the board lined to indicate contrasting colors.

The dominant features of my design reside in the full line portions shown.

I claim:

The ornamental design for a game board, substantially as shown and described.
